US0D1070912S

(12) **United States Design Patent** (10) Patent No.: **US D1,070,912 S**
(45) Date of Patent: ** Apr. 15, 2025

(54) **DISPLAY SCREEN OR PORTION THEREOF
WITH ICON OF ANALYSIS DEVICE**

(71) Applicant: **SHIMADZU CORPORATION**, Kyoto (JP)

(72) Inventors: **Kosuke Uchiyama**, Kyoto (JP);
Richard Price, Milton Keynes (GB)

(73) Assignee: **SHIMADZU CORPORATION**, Kyoto (JP)

(**) Term: **15 Years**

(21) Appl. No.: **29/915,616**

(22) Filed: **Nov. 2, 2023**

(30) **Foreign Application Priority Data**

May 31, 2023 (JP) ..... 2023-010993 D

(51) **LOC (15) Cl.** **14-04**

CLAIM

The ornamental design for a display screen or portion thereof with icon of analysis device as shown and described.

DESCRIPTION

The sole FIGURE is a front view of a display screen or portion thereof with icon of analysis device showing the claimed design.

The outermost broken-line rectangle illustrates the perimeter of a portion of a display screen and forms no part of the claimed design.

1 Claim, 1 Drawing Sheet
